UNITED STATES PATENT OFFICE.

GEORGE PAUL THOMAS, OF GLENSHAW, PENNSYLVANIA.

SPACING-TABLE MACHINE.

1,245,530. ~~Letters Patent~~ Specification of Letters Patent. Patented Nov. 6, 1917.

Application filed December 30, 1916. Serial No. 139,842.

To all whom it may concern:

Be it known that I, GEORGE PAUL THOMAS, residing at Glenshaw, in the county of Allegheny and State of Pennsylvania, a citizen 5 of the United States, have invented or discovered certain new and useful Improvements in Spacing-Table Machines, of which improvements the following is a specification.

0 In my U. S. Letters Patent No. 1,179,475 there is shown and described a spacing machine wherein the carriage itself is provided with two sets of coördinated locks, one for stopping the advance and the other the 5 bound movement of the carriage. The machine also contemplates, first, an advance of the carriage a short distance after the stopping parts have been brought into engagement with each other, and, secondly, a subsequent backward movement to the required 0 stopping point.

The object of my present invention is to provide a spacing machine of the same general character and for the same general purpose as that of the above named patent, but wherein the table is provided with stops rather than having all the stopping parts borne by the carriage. A further object of 0 my invention is, by improving the details of construction of such machine, to increase the efficiency thereof.

In the accompanying sheets of drawings forming part of my specification I have illustrated the preferred embodiment of my 5 invention. Figure 1 is a top plan view of the machine; Fig. 2 a side elevation thereof; Fig. 3 a vertical sectional view taken on the line III—III, Fig. 1; Fig. 4 a sectional view taken on the line IV—IV, Fig. 3; Fig. 0 5 a detail of construction explained herein-after; Fig. 6 a cross-sectional view of a modified form of spacing table; and Fig. 7 a sectional view taken on the line VII—VII, Fig. 6.

5 In the illustrative embodiment of my invention, referring first to Figs. 1 and 5, inclusive, there is shown but a portion of a spacing table, which may, as indicated, be constructed of a horizontal channel 1 and side channels 2. While the carriage may be constructed either to drag or support the material to be operated upon, the former arrangement is illustrated herein, the carriage consisting of a frame 3, trucks 4, and 0 a clamp 5 for engaging the material. For

moving the carriage it is provided with a rotatably mounted shaft 6 having a pinion 7 secured to it and which engages a rack 8 attached to the top 1 of the table. This shaft may be turned by a hand wheel 9, or otherwise, as desired.

In the practice of my invention the table has secured to it a plurality of stopping elements having oppositely disposed stopping faces, and the carriage is provided with 65 movable stop engagers adapted to engage such oppositely disposed faces of the stopping elements and thereby arrest the advance movement of the carriage as well as its subsequent rebound movement.

While various forms of stopping elements may be used, I preferably provide a detent bar 10 having, on its upper face, teeth with oppositely disposed stopping faces 11 and 11^a, as seen particularly in Fig. 5. The teeth 75 are preferably symmetrical so that in case they become unevenly worn the bar may be turned end for end. The stop engagers are preferably pivotally mounted, pawls 12 and 13 provided at their free ends with teeth 80 adapted to engage those of the bar 10. For reasons fully explained in my U. S. Patent No. 908,818, there are preferably a plurality of each of these pawls arranged side by side as seen in Figs. 1 and 4. Both sets of pawls 85 are pivotally mounted on a rigid member,

which may be a pair of bars 14, and which is mounted for reciprocatory movement in a direction substantially parallel to the line of advance of the carriage. As seen in Fig. 3, 90

the pawls 13, the rebound stop engagers, are provided at their upper ends with round holes through which there extends a pin 15 secured to the bars 14. These bars at their ends nearest the pin 15 are slidably mounted 95

in a housing 16. On the other hand, the pawls 12, the stop engagers for resisting the advance movement of the carriage, are provided with longitudinally-disposed slots 17, through which there extends a pin 18. This pin in turn passes through round holes in the bars 14 and is attached to a vertically disposed arm of a bell-crank lever 19, the horizontal arm thereof being pivotally connected to a rod 20 extending through a top plate 21 of the carriage and engaging the upper end of a buffer spring 22. An initial tension is placed on the spring 22, and the rod 20 is provided with shoulders adapted to engage the plate 21 for limiting the up- 110

ward movement of the rod in response to the action of the spring.

Means are provided for holding the pawls out of engagement with the stops, for releasing such holding means at the desired time to effect a stopping of the carriage, and for again bringing the pawls into engagement with the holding means. In the illustrative embodiment of my invention in its preferred form, the sets of pawls 12 and 13 are held in raised position by latches 23 and 24 secured, respectively, to rotatable shafts 25 and 26, mounted in the carriage frame 3. The shaft 25 is provided with a crank arm 27, connected by means of a link 28 to a finger 29, pivotally attached to a horizontal rod 30. In the advance of the carriage the finger 29 is tripped at the required intervals as by means of pins 31, which may be driven into a strip of wood 32. The finger being thus swung backwardly, the latch 23 is, through link 28, arm 27 and shaft 25, moved in the same direction to release the pawls 12, which then drop upon the detent bar 10. The pawls 13 are preferably released subsequently to the release of the pawls 12 and substantially coincident with the engagement of the pin 18 by the lower end of the pawl slot 17. For this purpose the latches 23 and 24 are provided with fingers 33 and 34, respectively, the former being adapted to engage, the latter to trip the latch 24. These fingers are, as indicated, so disposed one above the other as to accomplish the above stated successive releasing of the latches 23 and 24.

To raise the sets of pawls 12 and 13 from engagement with the detent bar, they are, by means of suitably slotted links 35 and 36, connected to the rod 30, which in turn is supported by lever arms 37 secured to a rotatable shaft 38. A suitable counterweighted arm 39 may be used to rotate the shaft 38. It will be observed that, in raising of the rod 30 to lift the pawls, the finger 29 is likewise raised so that it may swing beyond the engaged pin 31 to a position to be engaged by the next successive pin.

In the operation of this embodiment of my invention, the carriage is moved along the table by the rotation of the driving shaft 6. When the finger 29 strikes a pin 30 the finger is swung backwardly to turn the latch 23 to release the pawls 12 and permit them to drop into engagement with the detent bar 10. The further swinging of the finger 29 causes a further turning of the latch 23 to cause its finger 33 to engage the finger 34 of the latch 24, which latch comes to pawl-releasing position at substantially the same time the lower end of a slot 17 of the pawl 12 strikes the pin 18. The momentum of the carriage and its engaged load is then resisted and absorbed by the spring 22, the connections for this purpose between such spring and the

carriage frame including pawls 12, bell-crank lever 19 and rod 20. It is of importance to observe that, during the momentum-absorbing period of the movement of the carriage, the pawls 12 and 13 engaging the detent bar or stops are, by means of the bars 14, held against movement with relation to each other. That is to say, the pawls 13 are not, by this movement of the carriage, dragged over some of the teeth of the rack, which operation would result in the pawls being wedged against the teeth and hence become difficult to release from engagement with them. When the momentum of the carriage has become absorbed by the spring 22, such spring reacts to bring the carriage back to the position it occupied immediately preceding the downward movement of the spring-compressing rod 20. Any further backward movement of the carriage is then resisted by the rebound pawls 13. To release the pawls and set the machine for the next movement of the carriage it is only necessary to press downwardly the arm 39.

In the modification of my invention illustrated in Figs. 6 and 7, the rack or detent bar 10 of the machine just described is replaced with a plurality of separately adjustable stopping elements 40, provided with oppositely disposed stopping faces. Fig. 6 shows the horizontal table 41 as being provided with slots 42 to receive the heads of bolts 43 to hold the stops in their adjusted positions. Any other well known or suitable means may be used for fastening these stops. In this modification of construction there may be but single pawls 12^a and 13^a for resisting, respectively, the advance and rebound movements of the carriage. As indicated, the pawl 12^a is preferably provided with a round hole for engaging the pin 18. The pawls may be lifted from stop engaging positions and subsequently released by mechanism the same as that shown in, and described with reference to, Figs. 1 and 4, inclusive. On the other hand, the pawls may, if desired, slide upon the top of the table 41 between the stops 40, the pawl 13^a being beveled as at 44 to cause it to ride over the stops as the carriage is advanced. For raising the pawl 12^a to pass a stop, the arm 39, shaft 38, lever arm 37, and link 35 may be used.

It will be understood of this modification that the parts not shown and specifically described may be the same as shown in Figs. 1 to 4, inclusive, and already described.

According to the provisions of the patent statutes I have described the principle and operation of my invention together with the machine and its modifications which I now consider to represent the best embodiment thereof. However, it will be understood that my invention may be practised by other forms of machine than that particularly shown and described.

I claim as my invention:

1. In a spacing machine, the combination of a spacing table, a plurality of stopping elements secured at longitudinal intervals thereto and provided with oppositely disposed stopping faces, a carriage movable upon said table, two oppositely acting stop-engagers movably secured to said carriage and adapted to engage said oppositely disposed faces of said stopping elements, one of said engagers resisting the advance and the other the rebound movement of the carriage, and means for releasing the advance-resisting stop-engager from a stop. 60
- 5 2. In a spacing machine, the combination of a spacing table, a plurality of stopping elements secured at longitudinal intervals thereto and provided with oppositely disposed stopping faces, a work carriage movable upon said table, two oppositely disposed pawls pivotally connected to said carriage and adapted to engage said oppositely disposed faces of said stopping elements, one of said pawls resisting the advance and the other the rebound movement of the carriage, and means to release said pawls from the stopping elements. 65
- 10 3. In a spacing machine, the combination of a spacing table, a plurality of stopping elements secured at longitudinal intervals thereto and provided with oppositely disposed stopping faces, a work carriage movable upon said table, two oppositely disposed pawls pivotally connected to said carriage and adapted to engage said oppositely disposed faces of said stopping elements, one of said pawls resisting the advance and the other the rebound movement of the carriage, holding members for keeping said pawls out of engagement with said stopping elements, and means effective upon the advance of the carriage for releasing said holding means. 70
- 15 4. In a spacing machine, the combination of a spacing table, a plurality of stopping elements secured at longitudinal intervals thereto and provided with oppositely disposed stopping faces, a work carriage movable upon said table, two oppositely disposed pawls pivotally connected to said carriage and adapted to engage said oppositely disposed faces of said stopping elements, one of said pawls resisting the advance and the other the rebound movement of the carriage, holding means for keeping said pawls out of engagement with said stopping elements, and means effective upon the advance of the carriage for releasing said holding means. 75
- 20 5. In a spacing machine, the combination of a spacing table, a plurality of stopping elements secured at longitudinal intervals thereto and provided with oppositely disposed stopping faces, a work carriage movable upon said table, a rigid member mounted upon said carriage for reciprocating movement substantially parallel with the line of advance thereof, a momentum-absorbing buffer resisting the movement of said member in one direction, two oppositely disposed pawls pivotally connected to said member and adapted to engage said oppositely disposed faces of said stopping elements, one of said pawls resisting the advance and the other the rebound movement of the carriage, holding means for keeping said pawls out of engagement with said stopping elements, and means effective upon the advance of the carriage for releasing said holding means. 80
- 25 6. In a spacing machine, the combination of a spacing table, a detent bar secured thereto and provided with symmetrical teeth spaced at short equal longitudinal intervals and having oppositely disposed stopping faces, a work carriage movable upon said table, two oppositely disposed pawls pivotally connected to said carriage and adapted to engage said oppositely disposed faces of said teeth, and means for releasing said pawls from said teeth. 85
- 30 7. In a spacing machine, the combination of a spacing table, a detent bar secured thereto and provided with symmetrical teeth spaced at short equal longitudinal intervals and having oppositely disposed stopping faces, a work carriage movable upon said table, a rigid member mounted upon said carriage and for reciprocatory movement substantially parallel with the line of advance thereof, a momentum-absorbing buffer resisting the movement of said member in one direction, two oppositely disposed pawls pivotally connected to said carriage and adapted to engage said oppositely disposed faces of said teeth, holding means for keeping said pawls out of engagement with said teeth, and means effective upon the advance of the carriage for releasing said holding means. 90
- 35 8. In a spacing machine, the combination of a spacing table, a plurality of stopping elements secured at longitudinal intervals thereto and provided with oppositely disposed stopping faces, a work carriage movable upon said table, a rigid member mounted upon said carriage for reciprocatory movement substantially parallel with the line of advance thereof, a momentum-absorbing buffer resisting the movement of said member in one direction, two oppositely disposed pawls pivotally connected to said carriage and adapted to engage said oppositely disposed faces of said teeth, holding means for keeping said pawls out of engagement with said teeth, and means effective upon the advance of the carriage for releasing said holding means. 95
- 40 9. In a spacing machine, the combination of a spacing table, a plurality of stopping elements secured at longitudinal intervals thereto and provided with oppositely disposed stopping faces, a work carriage movable upon said table, a rigid member mounted upon said carriage and for reciprocatory movement substantially parallel with the line of advance thereof, a momentum-absorbing buffer resisting the movement of said member in one direction, two oppositely disposed pawls pivotally connected to said carriage and adapted to engage said oppositely disposed faces of said teeth, holding means for keeping said pawls out of engagement with said teeth, and means effective upon the advance of the carriage for releasing said holding means. 100
- 45 10. In a spacing machine, the combination of a spacing table, a plurality of stopping elements secured at longitudinal intervals thereto and provided with oppositely disposed stopping faces, a work carriage movable upon the table, a rigid member mounted upon said carriage for reciprocatory movement substantially parallel with the line of advance thereof, a momentum-absorbing buffer resisting the movement of said member in one direction, two oppositely disposed pawls pivotally connected to said carriage and adapted to engage said oppositely disposed faces of said teeth, holding means for keeping said pawls out of engagement with said teeth, and means effective upon the advance of the carriage for releasing said holding means. 105
- 50 11. In a spacing machine, the combination of a spacing table, a plurality of stopping elements secured at longitudinal intervals thereto and provided with oppositely disposed stopping faces, a work carriage movable upon the table, a rigid member mounted upon said carriage for reciprocatory movement substantially parallel with the line of advance thereof, a momentum-absorbing buffer resisting the movement of said member in one direction, two oppositely disposed pawls pivotally connected to said carriage and adapted to engage said oppositely disposed faces of said teeth, holding means for keeping said pawls out of engagement with said teeth, and means effective upon the advance of the carriage for releasing said holding means. 110

In testimony whereof I have hereunto set my hand.

GEORGE PAUL THOMAS.
